[57] CLAIM

The ornamental design for a rubber band gun, substantially as shown.

DESCRIPTION

FIG. 1 is a side elevational view of a rubber band gun showing my new design;

FIG. 2 is a side elevational view thereof showing the side opposite that shown in FIG. 1;

FIG. 3 is a front elevational view thereof;

FIG. 4 is a rear elevational view thereof;

FIG. 5 is a top plan view thereof; and,

FIG. 6 is a bottom plan view thereof.
